COMBINED TYPEWRITING AND COMPUTING MACHINE

Henry L. Pitman, Hartford, Conn., assignor to
Underwood Elliott Fisher Company, New York,
N. Y., a corporation of Delaware

Original application March 25, 1932, Serial No.
601,173. Divided and this application March
12, 1937, Serial No. 130,535

2 Claims. (Cl. 235—60)

This invention relates to computing mechanism in which computing wheels rotate in one direction for addition and in the opposite direction for subtraction, and also relates to a novel tens-carrying mechanism and novel means for preventing overthrow of the computing wheels. The invention is particularly applicable for modifying the well-known Underwood-Hanson computing machine for direct subtraction, thus greatly simplifying said machine, and for simplifying the tens-carrying mechanism and overthrow-preventing mechanism of said machine.

The Underwood-Hanson machine is described in the patent to O. Minton No. 1,280,065 dated September 24, 1918, which also discloses the Underwood subtraction mechanism, whereby subtraction is effected by adding the usual complement of the subtrahend.

Tens-carrying mechanism of the Underwood-Hanson machine is described in Patent No. 1,278,812 to H. Hanson, dated September 10, 1918.

According to the present invention, the subtraction-mechanism is much simplified in comparison with the Underwood subtraction mechanism described in the aforementioned patent to Minton No. 1,280,065. State-determining means are provided whereby the dial-wheels are caused to rotate in one direction for addition or to rotate reversely for subtraction. The subtraction is therefore "direct", as distinguished from subtraction effected by adding the complement of the subtrahend.

In the present invention, the register-bars having the computing wheel driving racks and the index-pins are retained. For addition the computing wheels are driven directly by said driving racks, whereas for subtraction the computing wheels are driven by intermediate rotation-reversing pinions or racks which may be permanently in mesh with the driving racks. The computing wheels are normally disengaged from both the driving racks and the intermediate pinions, and by the state-determining means are brought into mesh, either with the driving racks on the register-bars or with the intermediate pinions, during an initial portion of the advance movement of the general operator, depending on the setting of the state-determining means. Said state-determining means may be normally set or conditioned for addition so that normally the computing wheels will be directly driven by the driving racks on the register-bars. For subtraction said state-determining means may be conditioned as by the operation of a subtraction-key

to bring the computing wheels into engagement with the intermediate pinions.

The computing wheels remain in mesh throughout the rest of the advance movement of the general-operator cross-bar. Driving means for said general-operator cross-bar may be so arranged that at the end of said advance movement said general-operator cross-bar stands stationary for an interval of time to insure completion of the tens-carrying operation, as will herein-after be made clear, the return movement of the general-operator cross-bar being commenced at the end of said interval. In the initial portion of said return movement, the computing wheels are caused to be disengaged before the general-operator cross-bar picks up the advanced register-bars to restore them to their normal positions. By thus disengaging the computing wheels, before the return of the register-bars, the necessity for providing one-way connections of the computing wheels to the register-bars is avoided, with consequent simplification of the mechanism.

The carrying of tens from one computing wheel to another computing wheel of the next higher denomination involves the release of a spring-pressed normally latched register-bar stop through the movement of said first computing wheel past its carrying position. The register-bar stop in its normal unreleased position is effective to limit the movement of the register-bar for the computing wheel of next higher denomination, to the end that said register-bar may not be overthrown while being driven forward by the general-operator cross-bar. When said register-bar stop is released from its latch, and is, in consequence, caused to be withdrawn by its spring, the register-bar is permitted to advance an extra unit space to thereby carry over a tens value, said stop being still effective, however, to prevent overthrow of the register-bar, since it is only withdrawn enough to permit said extra advance.

If a register-bar stop be released and withdrawn before the general operator reaches the end of its advance movement, the register-bar which said stop controls is, according to an important feature of the invention, advanced positively for "carrying", by the movement of the general-operator cross-bar as it completes its advance stroke. To this end, the general-operator cross-bar does not engage the index-pins directly for advancing the register-bars, but there are interposed ahead of said cross-bar for engaging the index-pins, the ends of a series of levers of the first order pivoted on a fulcrum-rod carried by the general-operator cross-bar. The

other and normally free ends of said levers are, in the direction of cross-bar movement, opposite the free ends of a series of similar levers of the first order pivoted on a fixed fulcrum-rod, the other ends of said latter levers being connected to the aforesaid register-bar stops. The levers connected to said stops are capable of two positions, depending on whether or not the stop is withdrawn for carrying. If a stop is not withdrawn for carrying, the free end of the lever connected thereto just meets the free end of the opposite lever on the fully-advanced general-operator cross-bar. The two levers thus meeting form a pincer-like arrangement wherein the index-pin is held between the register-bar stop and the opposite end of the lever on said cross-bar, said cross-bar backing up said opposite lever end. Thus the advanced position of the register-bar is secured against overthrow and also against rebound. Should a register-bar stop be withdrawn before the general-operator cross-bar reaches the end of its advance movement, the free end of the lever connected to said register-bar stop will be moved toward the free end of the opposite lever on the approaching cross-bar and thus constitutes an interponent which will engage and arrest said free end of the cross-bar lever just before the cross-bar completes its advance movement.

It will be understood now that as said cross-bar advance movement is completed, the lever on the cross-bar will be rocked because of the arrest of its free end, thereby causing an extra tens-carrying advance of the register-bar, the extra advance being positive due to the positively driven cross-bar. The levers may be so proportioned that when a sufficient extent of carrying advance is reached, the index-pin is again held between the register-bar stop and the opposite end of the lever on the cross-bar to prevent overthrow or rebound of the register-bar. The free ends of the two series of levers may be proportioned and arranged so that the levers connected to the register-bar stops may lock the levers on the cross-bar against reverse movement at the end of a carrying movement of said cross-bar levers. Such proportioning and arrangement of said free ends are also effective to stabilize the levers connected to the register-bar stops as their free interponent ends co-operate to rock the cross-bar levers, inasmuch as the lines of reaction, which the free ends of said stop-levers afford to rock the cross-bar levers and lock the same against reverse rotation, may in either case pass through the fulcrum center of said stop-levers.

If, as may happen in some computations, a register-bar stop be released and withdrawn for carrying a tens value after the general-operator cross-bar has completed its advance movement, the carrying advance of the register-bar controlled by said stop may be effected by power derived from suitable springs connected either to the register-bar stop or its lever. In this case it will be understood that the free ends of the stop-lever and the opposite cross-bar lever just meet as the cross-bar completes its advance and that a subsequent release and withdrawal of the stop will cause the lever connected therewith to be rocked by the power of the aforesaid spring, with a consequent rocking of the lever on the cross-bar and a consequent carrying advance of the register-bar whose set index-pin is held between the register-bar stop and cross-bar lever as aforesaid.

It will be seen now that the cross-bar levers,

broadly considered, constitute rack-engaging fingers, which, in respect to said cross-bar or any other suitable movable member on which they may be mounted, may be advanced one unit-space, thus enabling said cross-bar or movable member which has a fixed extent of movement to advance the racks an extra unit-space for carrying. It will also be seen that the advance of said fingers in respect to the cross-bar, and hence the "carrying" of the register-bars, are in most cases accomplished positively.

In practicing the invention the register-bar stops may be in the form of elongate bars connected at one of their ends to their respective levers, said ends also forming the stop or abutment between which and the cross-bar lever or finger, the index-pin is held at the end of the register-bar movement. Said stop-bars, viewed sidewise of the register-bars, may extend substantially parallel to the latter and may be latched at their other ends over a latching bar. Each computing wheel may have the usual carrying tooth. Said tooth, in the preferred form of the invention, does not, for "carrying" as aforesaid, release the corresponding register-bar stop by direct engagement, but instead, for convenience of arrangement of the parts, releases said stop through an intermediate carrying lever, one end of which may be engaged by said carrying tooth, and the other end of which may engage the stop to displace the same from the latching bar. The tooth-actuated carrying levers may be mounted in the aforesaid frame, in which the computing wheels are mounted, and may be so arranged that the ends which engage the stops may properly engage said ends irrespective of the shifting of said frame either toward the register-bar racks or toward the intermediate racks.

This application is a division of my co-pending application Serial No. 601,173, filed March 25, 1932, (now Patent No. 2,078,274, dated April 27, 1937) which is a continuation in part of and co-pendent with my application No. 324,353, filed December 7, 1928 (now Patent No. 1,927,951, dated September 26, 1933).

Other features and advantages will hereinafter appear.

In the accompanying drawings—

Figure 1 is a cross-section through the combined typewriting and computing machine, showing, in side elevation, details of the novel carrying mechanism.

Figure 2 is a side elevation, showing details of one form of power-drive for the computing mechanism.

Figure 3 is a detail view, showing the construction of means whereby a universal bar for restoring the carrying stops is operated.

Figure 4 is a top plan view, looking down on the computing mechanism, to show the arrangement of four registers, and the operating parts for said registers.

Figure 5 is a skeleton view, showing, in perspective, the arrangement of said four registers, and the arrangement of a register-bar, relatively to the novel carrying means, and also bringing out other details of construction.

Figure 6 is a skeleton view, showing, in perspective, the fixed plates within which a register-wheel frame is shifted, and also showing, in detail, means for ensuring relatching of carrying stops.

Figure 7 is a view, showing, in perspective,

details of operating connections associated with a latching bar for the carrying stops.

Figure 8 is a detail front view, showing how said latching bar is supported in the aforesaid fixed plates.

Figure 9 is a side view, illustrating means and the operation thereof for shifting the aforesaid latching bar.

Figures 10 and 11 are enlarged side views, showing details of the novel carrying mechanism, Figure 10 showing said mechanism in normal position, and Figure 11 showing said mechanism operated to effect the "carrying" of a number.

Figures 12, 13 and 14 are each a side view of a register-bar and the train of carrying parts extending from one computing wheel to the register-bar of next higher denomination. Figure 12 shows a computing wheel directly engaged with the register-bar for addition, and also shows a register-bar in advanced position without having carried. Figure 13 is similar to Figure 12, but shows the register-bar advanced for carrying. Figure 14 shows a computing wheel not directly connected to the register-bar rack, but connected thereto by the intermediate pinion to reverse the rotation of said wheel for subtraction. Figure 14 also showing the register-bar advanced for carrying, and, compared with Figure 13, showing that the carrying advance of a register-bar is the same for subtraction as it is for addition.

Figures 15 and 16 are partial plan views of means forming the power-drive shown in Figure 2.

As seen in Figure 1, the novel computing mechanism co-operates with a typewriter in which numeral-keys 10 mounted on key-levers 11 may, through other members of the usual type-action, cause types 12 to print against a platen 13. Said platen 13 is in a carriage 14 traveling on rails 15 and 16 of the typewriter-framework 17. By operation of the type-keys said carriage is propelled in letter-feeding steps determined by an escapement-mechanism 18 under control of said keys and spring-motor 19.

The computing mechanism may include one or more sets of computing wheels 20, Figure 4, indicating four sets of computing wheels. For each computing wheel there is a register-bar 21 carrying a series of downwardly-settable index-pins 22, for the digits from "0" to "9". As disclosed in my co-pending Patent No. 1,869,582, dated August 2, 1932, only one pin at a time may be set in a bar, the setting of one pin in a register-bar being effective to force any previously-set pin in said bar back to its normal position by means represented by cam-blocks not shown, interposed between the stop-pins and fully described in said co-pending Patent No. 1,869,582, the cam-blocks, briefly explained, being displaced longitudinally of the register-bar upon depression of any pin, and by reason of their cam-formations being capable of restoring a previously-set pin as they are displaced. The "0" pin in each register-bar is normally set, and is, of course, restored by the setting of any higher pin in a register-bar.

For setting an index-pin in any register-bar, each numeral-key lever 11 has depending therefrom a stem 24, to rock a shaft 25, each key-lever having its own shaft. The several shafts 25 are for actuating parallel motion pin-setting linkages 26, one for each numeral-key. Each linkage includes a pin-setting bar 27 movable edge-wise and downwardly upon operation of said linkage by its numeral-key.

The pin-setting linkages are of the type shown in the aforementioned patents to Minton and Hanson. Each pin-setting bar 27 is connected at each end to a horizontal arm of a bell-crank, not shown, vertical arms of said bell-cranks being connected to the ends of an upper bar 28. Arms 29 connect the rock-shafts 25 to the upper bars 28 of their respective linkages, each shaft also having fast to its end a horizontally-extended arm 30 engageable by the numeral-key stem 24.

Index-pins are set in the register-bars as the carriage moves predetermined zones of a work-sheet past the printing point. As indicated in Figure 1, downward movement of a pin-setting bar 27 is ineffective to set a pin in a register-bar unless the bar is slightly advanced to bring the pins therein under the pin-setting bars 27. This advance is accomplished seriatim for the several register-bars by the movement of the typewriter-carriage 14 in presenting the aforesaid work-sheet zones to the printing point. To this end, said carriage may carry tappets 31 settable along rails 32 of said carriage according to the location of zones of carriage travel in which index-pins are to be set. By the step-by-step movement of the typewriter-carriage 14 in such zone, a tappet displaces, in seriatim order, the ends 34 of jacks 35, and thereby depresses push-rods 36, to rock levers 37, each lever having one arm 38 connected to a push-rod as shown, and another arm 39 connected to one end of a transposing linkage 40, the other end of said linkage 40 pushing upon a pin 41 projecting from the side of a corresponding register-bar. According to the usual practice, the tappets 31 are offset from one another, see Figure 1, each tappet being mounted on a dog 33. By such offsetting one tappet is effective on only one set of jacks 35 and ineffective on other sets of jacks 35, according to which set or sets of register-bars 21 shall be indexed.

With the typewriter-carriage 14 in a computing zone, a push-rod 36, corresponding to the column of the work-sheet zone which is at the printing point, will have been depressed by means of the tappet 31, and the register-bar 21 connected thereto will be advanced, so that its index-pins 22 are under the pin-setting bars 27. Operation of a numeral-key now will cause the corresponding pin-setting bar 27 to descend and set a corresponding index-pin 22. The carriage 14 then escapes, releasing said push-rod 36 and causing the corresponding register-bar to be retracted by means of a spring-device 42. In the meanwhile, the push-rod 36 for the next column will have been depressed as the carriage took its letter-feeding step and the next register-bar will have been advanced to bring its index-pins under the pin-setting bars. In this manner is the pin-setting accomplished seriatim for the register-bars as the carriage moves a computing zone of the work-sheet, column by column, past the printing point.

The transposing linkages 40 transpose the seriatim order, in letter-feeding direction, of push-rod operation into the proper but reverse order of the seriatim indexing of the register-bars, each linkage 40 including a bell-crank 40a which engages the pin 41.

The index-pins 22 are set into the path of register-bar-engaging fingers 43 formed at the upper ends of levers 44, carried by a cross-bar 45 movable forward and back for advancing the register-bars and returning the advanced bars. The purpose of said levers, which is to provide for extra carrying advance of the register-bars, and

the co-operating parts, will be explained further on.

For moving the cross-bar 45 in the direction in which it is to advance and return the register-bars 21, there are employed the usual racks 46 guided for reciprocatory endwise movement along the inner sides of side members 47 of the computing-mechanism framework. Said racks 46 carry plates 48 provided with slots 49 in which tenons 50 at the ends of said cross-bar are inserted. Said slots 49 are longer than is the width of said tenons, so that the cross-bar may slide edgewise in said slots for a purpose to be explained. By moving both racks 46 in unison, the cross-bar 45 10 may be moved without skewing, and, to this end, said racks are coupled by a cross-shaft 52 journaled in said framework side members 47, and having gear-sectors 53 fastened thereto, one at each end of said shaft, aligned with said racks 20 46, see Figure 4. Said gear-sectors are not directly connected to the racks, but are connected thereto by intermediate pinions 54, mounted on the side members 47, to give the racks 46 the right direction of movement in respect to reciprocatory 25 rotation of the cross-shaft 52, which may have connected thereto an operating handle (not shown), for hand operation of the computing mechanism. For operation by power, there may be used the power-drive shown in the patent 30 to F. A. Hart, No. 1,171,403, dated February 8, 1916, said mechanism presenting a driver 55, which, driven by a crank (not shown), reciprocates forth and back in the direction of movement of the racks 46 and register-bars 21. Connection 35 between said driver 55 and the racks 46 is made by means of the usual member 56, which embraces said driver, as seen in Figure 1, and which is fastened to the under side of the left-hand rack 46, said driver being positioned sidewise 40 of the machine to align with said left-hand rack 46. For disengaging the power-drive, the casting 51, from which the driver 55 projects, may be lowered in the usual manner, to thereby withdraw said driver 55 from the member 56. When 45 the driver 55 is thus withdrawn, the computing mechanism may be hand operated by means of the aforesaid handle (not shown).

By means of the usual key-operated clutch not shown herein, but shown in said Hart patent, 50 the driver 55 is normally disconnected from the motor-drive and is stationary in the position shown in Figure 1. By means of said clutch and its controlling key, the driver is connected to the motor-drive long enough to impart just one forth-and-back movement to said driver and hence to the cross-bar 45.

When the cross-bar 45 has advanced and carried the register-bars 21 forward, to extents determined by whichever digit-pins 22 were set, in 55 the several register-bars, there must be a suitable period of time during which certain carrying operations may take place, as will hereinafter be explained. That is, said cross-bar 45 must not immediately start its return movement after completing its advance movement, because such immediate return movement would in some cases return certain register-bars 21 before they had time to "carry". To hold the cross-bar 45 stationary for a sufficiently long carrying period, 60 the last portion of the forward stroke of the driver 55 and an initial portion of the return stroke of said driver are rendered ineffective to move the cross-bar 45, said driver 55 moving forth and back as usual, but the time-period of said portions of 65 its strokes being apportioned to said carrying

operations. It is to this end that said cross-bar is movable edgewise in its retaining slots 49 of the rack-plates 48, it being understood that said plates 48 will move with the drive. 55 throughout the full range of movement of said driver, and that the cross-bar 45 alone is held stationary just before and just after said driver 55 completes its forward stroke. For thus holding said cross-bar 45 stationary, there may be mounted and fastened on each framework side member 47 a plate 10 51, in which is formed a cam-slot 58, the plates being disposed, as best seen in Figure 4, between the racks 46 and the walls of the side member 47. On each rack 46 there is pivoted at 59 on a suitable stud, as shown, a bell-crank lever 60, having 15 a horizontal arm 61 for engaging the cam-slot 58 and an upright arm 62 connected to the cross-bar 45 by a link 63, the latter having a pivotal connection 64 to said arm 62. The horizontal arm 61 carries a roll 65 for engaging the cam-slot 58. 20 The arms 61, 62 of said lever are on opposite sides of the rack 46 and are joined by a cross-piece 66 (Figure 4), forming part of said lever 60. The link 63 is attached at one end to the cross-bar by screws 67, there being provided sufficient play between the sides of the slot 49 and the tenon 50 to avoid binding between said tenon and slot as the lever 60 rocks.

The range of forth-and-back movement of the driver 55 may, as in the case herein illustrated, be 30 just enough for full advance and return of the register-bars 21. In such case, if the aforesaid portions of driver-movement preceding and following its most advanced position are rendered ineffective to move the cross-bar 45, so that there 35 may be afforded time for carrying, it follows that said cross-bar 45 must in some other manner still receive the same extent of movement as the driving member 55. To compensate for the idle portion of the forward movement of the driver 55, 40 the cam-slot 58 is sloped downwardly at 69. This downward slope through the medium of the lever 60 causes an advance of the cross-bar 45, relatively to the racks 46 and plates 48, sufficient to compensate for the movement lost through the 45 idle portion of the forward stroke of the driver 55. When said driver starts its idle portion of stroke, it is rendered ineffective to further advance the cross-bar 45. This is accomplished by a reverse movement of the lever 60, the cam-slot 50 58, to this end, including an upturned portion 70, so formed that the cross-bar 45 is held stationary because of the reverse movement imparted to the lever 60 by said upturned portion 70 while the driver 55 completes its forward stroke. As the 55 driver 55 thus completes its forward stroke, the roll 65 will have reached the position shown in full lines in Figure 11. The broken lines, indicating the roll 65 and the driver 55, indicate, with reference to the full-line positions of said roll and 60 driver, some measure of the idle part of the stroke of said driver 55. It will be evident that at the beginning of the return stroke of said driver 55, there is also an idle portion in which the cross-bar 45 is not moved while the roll 65 rides down 65 the cam-slot portion 70 with consequent rotation of the lever 60. Also, in said return movement of the driver 55, the cam-slot portion at 69 will be effective to extend the return movement of the cross-bar 45 sufficiently by means of said 70 lever 60 to fully restore the register-bars 21. The cross-bar 45 in its fully returned position may abut stops 68a, Figures 4, 10 and 11.

Another form of cross-bar-driving mechanism is indicated in Figures 2, 15 and 16. In this lat- 75

ter form, the revolution of a roller 73, driven in a circle by a motor 74, is translated into reciprocatory movement of the cross-bar 45 by means of a link 75 fastened to said cross-bar and projecting rearwardly therefrom. The link 75 has at its rear end a head 76 forming a face 77 which the roller 73, revolving in the direction of the arrow, Figure 15, may engage to push the link 75 forwardly, said roller 73 in its initial position being as indicated in Figure 16. When the revolution of the roller 73 has advanced the link 75 sufficiently, said roller idly passes a curved portion 78 of the face 77, said curved portion 78 being at this time concentric with a stud 79 about which said roller 73 revolves on a plate 80. The period of this idle movement of the roller 73 before it begins to retract the link 75 and cross-bar 45 is utilized to insure in this form of drive the completion of "carrying operations", already mentioned. The cross-bar 45 is, where this form of power-drive is employed, fixed in the plates, designated in Figures 2 and 15 by reference numbers 48^a, no movement of said cross-bar relative to said plates being required.

As seen in Figure 15, the curved portion 78 is preferably so designed that the idle movement of the roller 73 may be about evenly apportioned on either side of the extreme forward position which said roller reaches, the length of said curved portion 78 depending on the time interval to be allowed for "carrying" before retraction of the link 75 is commenced. Figure 15 indicates by the broken circle at the right the position of the roller 73 at that point of its revolution about the stud 79 where it commences the return of the link 75. For returning the link 75 the roller 73 reacts against a face 82 of said link. Inasmuch as the roller 73 in that part of its revolution in which it moves forward can have no effect on said face 82, the latter does not extend beyond the position from which said roller begins its forward movement. Moreover, by thus limiting the extent of the face 82, it is feasible to move the cross-bar 45 forwardly independently of said roller, as in hand-operation, in which case the normal position of the roller may be as indicated in Figure 16. The face 82 may for a portion of its length be concentric with the curved portion 78 of the face 77, thereby giving acceleration to the final part of the return movement of the link 75 and keeping the roller 73 in contact with the face 77—78.

The roller 73 revolves only when the register-bars 21 are to be advanced for the accumulation of a number and returned, and is, to this end, connectible to the motor 74 by a clutch (not shown) such as is shown in the aforesaid patent to F. A. Hart, which clutch with reduction gearing 83 may be enclosed in a casing 84 extending from the motor 74 and which may carry the aforesaid stud 79 around which the roller 73 revolves and which stud is spaced from the driven clutch-shaft 85, for arrangement of the parts as indicated. Said shaft 85 may be connected to the roller-carrying plate 80 by a pinion 86, fast to the shaft 85, and a meshing pinion 87, fast to the plate 80. The motor 74 may be supported on a base 68 of the computing machine.

Each computing wheel 20 has fastened thereto a pinion 89. As seen in Figure 12, the pinions 89 may mesh with racks 90 formed at the forward ends of the pin-bars 21, or, as seen in Figure 14, the pinions may be driven by said racks 90 through intermediate pinions 91, which may be permanently in mesh with the racks 90. As in-

dicated in Figures 1 and 10, the computing-wheel pinions, and hence the computing wheels, are normally disengaged from both the pin-bar racks 90 and the intermediate pinions 91. Direct engagement of the computing wheels with the racks 90 causes them to revolve clockwise during a forward movement of the pin-bars 21. On the other hand, if the computing wheels be driven through the intermediate pinions 91, during said forward movement of the pin-bars 21, their rotation will be counter clockwise. One direction of rotation of the computing wheels may be for addition, and the opposite direction may be for subtraction. According to the arrangement of the dial-wheel numbers, as herein indicated, the clockwise rotation of the computing wheels, when directly driven by the racks 90, corresponds to addition, and the counter clockwise rotation of the wheels, when driven through the intermediate pinions 91, corresponds to subtraction.

To shift the computing wheels 20 either downwardly for engagement with the register-bar racks 90, or rearwardly for engagement with the intermediate pinions 91, said wheels 20, independently rotatable on a spindle 92, are retained with said spindle in a shiftable frame 93 having side plates 94 spaced apart so that the ends of said spindle 92 may be journaled therein. Said side plates 94 may be spaced apart by a cross-member 95, and by the spacing afforded by the series of computing wheels and the hubs or collars 96 adjacent to the outer computing wheels. The computing-wheel frame 93 is held against lateral displacement between fixed plates 97, which may be secured to, and project upwardly from, a front cross-member 98 of the computing mechanism framework, said cross-member 98 serving with a rear cross-member 99 to space apart the aforesaid side members 47 of said framework.

For supporting the computing-wheel frame 93 between said fixed plates 97, so that it may be shifted, there may be used a cross-rod 100 supported by and spanning said plates 97. Slots 101 at the rear end portions of the computing-wheel-frame plates 94 embrace said cross-rod, and when the computing-wheel frame is in normal position, in which the computing wheels 20 are disengaged, said slots 101 extend in a horizontal direction. The forward portion of the computing-wheel frame may be supported on arms 102 projecting from a rock-shaft 103, each computing-wheel frame being provided with one of said arms, as shown in Figure 4. Each arm 102 has a slot 104 which, when the frame 93 is in normal position and the computing wheels are disengaged, extends in a horizontal direction. Said slot 104 embraces the cross-member 95 of the computing-wheel frame.

From Figure 1 it will be seen that the slots 101 and 104 guide the frame for rearward and forward shifting, the rearward shifting being effective to engage the computing wheels with the intermediate pinions 91, the forward shifting of said frame conversely disengaging the computing wheels from said intermediate pinions 91. Figure 14 indicates the computing wheels engaged with said intermediate pinions.

From Figures 1 and 11 it will also be seen that the frame 93 may turn about the cross-rod 100 as a fulcrum, such turning being effected by rocking the shaft 103. In this case the computing wheels 20 will be directly engaged with the pin-bar racks 90, as indicated in Figures 11, 12 and 13.

Preparatory to the forward movement of the 75

register-bars 21, the computing wheels are brought into engagement with either the register-bar racks 90 or the intermediate pinions 91, and similarly, preparatory to the return movement of the register-bars, the computing wheels are disengaged again so as not to be reversed by the return movement of said register-bars.

Selective connections (not shown), for coupling the driving mechanism of the computing machine to the rock-shaft 103 or to a link 106, may be provided for effecting shifting of the computing-wheel frames 93 at the proper times during a computing-machine cycle. The rock-shaft 103 may be split into individual rock-shafts, one for 10 each of the registers, to control the registers independently, or there may be one rock-shaft common to all the registers, and it will be understood that said selective connections may be made accordingly. Such selective connections predetermine 15 whether the computing-wheel pinions 89 are to be presented directly to the racks 90 as for addition, or whether they are to be presented to the intermediate pinions 91 as for subtraction. The fixed plates 97 may have two-ways slots 107, into 20 which the computing-wheel spindles 92 may extend, so that their ends may receive screws 97a, whose heads bearing against the outer surfaces of said plates 97 serve to retain said spindles endwise. Horizontal and vertical branches of said 25 two-way slots 107 serve to hold the frames 93 against displacement transversely of said branches.

As already stated, the levers 44 on the general-operator cross-bar have register-bar-engaging fingers 43 for pushing the register-bars forward. How said levers 44 and their register-bar-engaging fingers operate to advance the register-bars 21 extra unit-spaces for carrying, will now be explained. Said levers 44, of which there is one for every register-bar, may be 30 mounted on a common fulcrum-rod 108, and there may be one such fulcrum-rod for every set of register-bars of the computing mechanism retained between ears 109 of a bracket 110 secured to the cross-bar 45, said ears projecting 35 downwardly and forwardly from said cross-bar. The levers 44, individually rockable on their fulcrum-rods, are spaced apart and located, as by collars or hubs 111, Figure 4. The register-bar 40 engaging fingers 43 of said levers 44 are aligned with the pins 22 of their respective register-bars, and may be formed by tabs bent at right angles to said levers.

The carrying of a tens value from one computing wheel to a wheel of next higher denomination is, according to the present invention, effected by advancing the register-bar for said higher wheel an extra unit-space, the extra advance being effected by causing the lever 44 to be rocked counterclockwise from the position seen in Figure 12 to the position seen in Figure 11, 13 or 14. As seen in Figures 10 and 12, a register-bar-engaging finger 43, backed by the cross-bar 45, may advance a register-bar by engaging a depressed pin 22. The advance of the cross-bar 45 and hence of the fingers 43 thereon, when abutting the forward side of said cross-bar, is always to the same extent, and the extent of advance of a register-bar therefore depends upon which index-pin is depressed. If the "0" pin, which is the first pin from the front of the machine, is not displaced from its normally-depressed position by the setting of a higher pin, the register-bar will not be advanced, 50 because the position which the cross-bar, with

the corresponding finger 43 bearing thereagainst, reaches at the end of its advance movement is such that said finger 43 just touches the depressed "0" pin. If a "1" pin is depressed, the register-bar will be advanced until said "1" pin is in the position from which the "0" pin moved in such advance of the register-bar. Similarly, by depression of a higher pin, the register-bar will be advanced until said higher pin is in the position which the "0" pin left in said advance.

Thus, it will be seen that, irrespective of the value of the depressed pin 22, the depressed pin always reaches the same position, and that it is therefore feasible to provide stops which will prevent overthrow of the register-bars as they reach the ends of their respective advance movements, and that said stops will be effective for any extent of said advance movements as determined by the values of the depressed pins 22. A stop 112 for each register-bar is therefore provided and is caused to abut the forward side of the depressed pin as a register-bar carrying said pin reaches the end of its advance position.

Two conditions govern the application of the stops 112, one condition being that said stops must be individually shiftable to permit an extra carrying advance of their respective register-bars, the other condition being that said stops, when the computing mechanism is in its normal condition, that is to say, when the register-bars are not being advanced to accumulate a number, must be sufficiently removed from the normally depressed "0" pins to permit the aforesaid slight advance of the register-bars seriatim during the indexing of the register-bars.

To these ends, the register-bar stops 112 may be formed on the rear ends of elongate bars 113, which are to be shiftable simultaneously from a normal position, indicated in Figure 1, wherein the stops 112 are far enough removed from the depressed "0" pins, as seen in Figure 1, to permit the aforesaid seriatim advance of the register-bars, to the position indicated in Figure 12, and more clearly indicated in Figure 10 by the dot-and-dash outline of a stop 112, in which latter position the stops 112 may abut the depressed pins of the advanced register-bars or the "0" pins of the register-bars that are not advanced. From said latter position, the bars 113, and hence the stops 112, are to be individually movable in a forward direction to permit an extra carrying advance of the corresponding register-bars, the forward carrying movement of the bars 113 being limited, however, so that the stops 112 are also effective to prevent overthrow of the register-bars when said register-bars carry. The forward carrying movement of any bar 113 is also utilized to effect, as will be explained, a carrying displacement of the corresponding lever 44 and its register-bar-engaging finger 43.

To these ends, the bars 113 are urged forward by individual springs 114, but are normally latched in non-carrying positions over a transverse latch-bar 115, each bar 113 having a latching edge 116, which normally abuts the rearward edge of said bar 115. The several bars 113 are pivotally connected at their rearward ends to upstanding arms 117 of levers 118 of the first order individually rockable on a fixed fulcrum-rod 119. Arms 120 of said levers 118 extend, in the normal positions of said levers as seen in Figure 1, downwardly and rearwardly. To effect rearward movement of all the bars 113 to bring the stops 112 from the positions seen

in Figure 1 to the position seen in Figure 10 or 12, in which latter position the stops are effective to prevent overthrow of the register-bars, the latch-bar 115, together with all the bars 113 latched thereover, is advanced rearwardly during the advance movement of the cross-bar 45 as will later on be explained. As the bars 113 are so moved simultaneously, their levers 118, mounted on the fixed fulcrum-rod 119, are rotated clockwise, so that the arms 120 of said levers 118 are shifted from the position indicated in Figure 1 to the position indicated in Figure 12. Said latter position of the arms 120 is such that pins 121 therein just abut downwardly-extending arms 122 of the corresponding levers 44 on the cross-bar 45 when the corresponding register-bars register a non-carrying advance, as indicated in Figure 12. From Figure 12 it will be seen that, with the arm 122 abutting the pin 121 and the register-bar-engaging finger 43 abutting the cross-bar 45, and the bar 113 latched over the bar 115, a register-bar whose depressed pin 22 is closely confined between the stop 112 and finger 43 is secured not only against overthrow, but is also secured against rebound.

Referring to Figures 10 and 11, it will be further seen that upward displacement of the forward end of one of the bars 113 will cause said bar to move forwardly under the pull of the spring 114.

As a bar 113 thus released from the latch-bar 115 moves forwardly, it rocks its lever 118 counterclockwise to the position seen in Figures 11, 13 and 14, and which position may be determined as by abutment of the lever 118 against a transverse rod 123 supported by and spanning the fixed plates 97 of each register. It will be evident that a lever 118, thus rocked counterclockwise by release of its bar 113, will also cause the corresponding lever 44 on the cross-bar 45 to be rocked counterclockwise, thereby causing the register-bar-engaging finger 43 on said lever 44, and hence the corresponding register-bar itself, to be advanced in respect to said cross-bar 45. Thus each register-bar may receive an extra movement depending upon the release of a bar 113. To prevent the levers 44 from falling into a disabling position when not engaging an index-pin 22, as, for example, when the cross-bar 45 is fully returned, each lever 44 may have an arm 124 to limit its counterclockwise movement, as is indicated, Figure 11, by the abutment of said arm with the bracket 110 attached to said cross-bar 45.

The release of a bar 113, as aforesaid, is to be effected every time a computing wheel, of next lower order to the register-bar controlled by said bar 113, passes its carrying point, and each computing wheel has therefore, projecting from its periphery, a carrying tooth 125. On account of the different positions of the computing wheels in addition and subtraction, the carrying teeth 125 of the several wheels operate to release the bars 113, preferably through intermediate carrying levers 126 individually rockable on a fulcrum-rod 127 supported between the side plates 94 of the computing-wheel shift-frame 93, and spaced and located on said rod 127 as by collars or hubs 128, Figure 11. Each carrying lever 126 has a cam-shaped arm 129 arranged so that said carrying lever may be rocked by the carrying tooth 125 in either direction of rotation of the computing wheel. As a carrying lever 126 is rocked, the end of an arm 130 thereof moves upwardly against and displaces the forward end

of a corresponding bar 113, and thus releases said bar 113 from the latch-bar 115.

The location of the ends of the arms 130 of the levers 126 is so arranged with respect to the cross-rod 100 that said ends of the arms 130 describe an arc or line when the computing-wheel shift-frame 93 is swung around said cross-rod 100 for engaging the computing wheels directly with the register-bar racks 90, which is substantially the same as the line along which said ends of the arms 130 move as the computing wheels are shifted rearwardly with said frame 93 for engagement with the intermediate pinions. Thus the carrying levers 126 are effective in either adding or subtracting position of the computing wheels 20, to release their respective bars 113.

A carrying train from any computing wheel to the register-bar of the computing wheel of next higher denomination includes the carrying lever 126 actuated by the former computing wheel, the bar 113, releasable by said carrying lever 126, the lever 118, connected to the rear end of said bar 113, and the lever 44, controlled by the latter lever 118, the register-bar engaging finger 43 of said lever 44 being aligned with the pins 22 of the register-bar of the computing wheel of said next higher denomination. Thus, one end of said train is the arm 129 of the carrying lever 126, and is adjacent the computing wheel of lower denomination, and the other end of said train is the register-bar-engaging finger 43 for the register-bar of next higher denomination. The required offset of said ends of the train may be effected by forming and arranging the parts thereof as indicated in Figures 4 and 5. As indicated in Figure 5, the carrying lever 126 may be within the plane of rotation of the carrying tooth 125. The forward portion of the bar 113 is aligned with said lever 126, the rear portion 40 of said bar being offset to the left by bends 132 and having the stop 112 formed by a tab bent to the left to align with the pins 22 of the register-bar of next higher denomination. The lever 118 is pivoted on the left side of said bar 113 and 45 its pin 121 projects to the left to align with the arm 122 of the lever 44 for said register-bar. Said lever 44 has its finger 43 in the form of a tab bent as shown to align with said pins 22 of said register-bar.

Each bar 113 is connected to its lever 118 by a headed pivot-stud 133. The levers 118, individually rockable on their fulcrum-rod 119, may be spaced and located on said rod as by hubs or collars 134, each register having one of said rods 55 which is supported by and spans the fixed plates 97. Although the units register-bar never carries, it is nevertheless provided with a bar 113, a lever 118 and a lever 44, the latter having its register-bar-engaging finger 43, inasmuch as 60 these parts also prevent overthrow and rebound of the units register-bar. No carrying train extends from the computing wheel of highest denomination, which is the first wheel from the left of the register.

In most cases, the levers 44 are rocked positively by the positively-driven movement of the cross-bar 45 itself when carrying is to be effected and therefore an extra carrying advance of a register-bar is effected positively. That is to 70 say, in most cases carrying bars 113 will have been released, and the levers 118, connected thereto, will have been rocked before the cross-bar 45, with its register-bar-engaging levers 44, effects contact of the arms 122 of said latter 75

levers with the pins 121 of the arms 120 of levers 118. Thus, said arms 120 and their pins 121 form interponents which, by the release of their respective bars 113, are thrust into the path of the advancing cross-bar levers 44 on the cross-bar 45. It will be seen, therefore, that as the arms 122 of the cross-bar levers encounter the pins 121, thus thrust into said path, the cross-bar levers 44 will be caused to rotate counter-clockwise to an extent equivalent to advancing their register-bars an extra unit-space, and which extent, it will be understood, may be determined by suitable proportioning and arrangement of the parts as illustrated in the drawings. In those cases where a carrying advance of a register-bar is effected, after said register-bar has reached its advanced position, as indicated in Figure 12, the necessary carrying displacement of the parts involved is effected by the power afforded by the spring 114.

The lever 118, whose arm 120 is thus thrust into the path of the advancing cross-bar lever 44, is to be stabilized against counter-rotation while it co-operates to rock said cross-bar lever 44, and the latter lever 44 is also to be locked against counter-rotation after it has been rocked to the position of Figure 11, 13 or 14. To this end the arm 122 of the lever 44 has an edge 136 extending in such direction relatively to the fulcrum of the lever 118, and clearly indicated in Figure 12, that said lever 118, if it is caused to be rocked by unlatching of the bar 113, may correspondingly rock the cross-bar lever 44. At the end of this rotation of the two levers 44, 118, the pin 121 of lever 118 arrives opposite a scooped-out portion 137 of said edge 136. A point or hump 138, at the intersection of the edge 136 and its scooped-out portion 137, affords such point of contact with the pin 121 as the lever 44 reaches said pin after the latter has already been thrust out, as aforesaid, that the lever 44 is rocked spaced and located on said rod 127 as by collars 128 completing its advance movement.

As indicated in Figure 11, said point or hump 138 approaches and makes contact with the pin 121 on the dot-and-dash line 139. In the ensuing rocking of the lever 44 to the position shown in Figure 11, 13 or 14, as the point or hump 138 is thus arrested while the cross-bar completes its advance, it will be seen that the line of reaction afforded by the lever 118 is to be substantially through or on a favorable side of the fulcrum-center of said lever, and hence there is substantially no tendency to rock said lever contrariwise, and therefore there is substantially no tendency to relatch the bar 113. As the lever thus, in the latter case, is rocked to the position shown in Figure 11, the scooped-out portion 137 settles against the pin 121. Since said portion 137 may, at its final point of contact with the pin 121, be substantially perpendicular to the aforesaid line of reaction through the fulcrum-center of the lever 118, as is clearly indicated in Figure 11, the lever 44 is also secured against counter-rotation after it reaches said position, and hence there is no tendency to rebound of the register-bar, even when said bar receives an extra advance for carrying.

The stop-bars 113 are spaced laterally and guided at their forward ends by a slotted transverse bar 140, which may also have slots 141, in which the front portions of the register bars 21 are guided. The stop-bars 113 are notched at their front ends to form an upper branch 113^a which is received by a slot in said transverse bar

140 and a lower branch 113^b which underlies said transverse bar to limit the upward movement of the forward end of a stop-bar 113. Said register-bars may be guided at their rear portions in slotted transverse plates 142, secured to the cross-member 99 of the framework. Said transverse bar 140 may be retained between the fixed plates 97, which retain the computing-wheel frame 93 against lateral displacement. Each pair of said fixed plates may have rearward extensions 143, between the ends of which may be retained the fixed fulcrum-rod 119 and abutment-rod 123 of the levers 118.

Each of a pair of said fixed plates 97 may have a slot 144, the opposite slots of the pair of plates serving to retain the latch-bar 115 whose ends may be guided in said slots, as indicated in Figures 5 and 8. The shifting of said bar back and forth in said slots 144 is effective not only to bring the register-bar stops 112 into and out of their stopping positions, as aforesaid, but the forward shifting of said latch-bar 115 is also effective to cause the relatching of those stop-bars 113 which have been released. With the position of the parts as seen in Figure 11, 13 or 14 in which the released bars 113 are held by abutment of their levers 118 against the rod 123, it will be evident that shifting of the latch-bar 115 forward, that is, toward the left, to the position indicated in Figure 1 or 10, is effective to relatch the released bars.

All of the latch-bars 115 of the several registers are thus shifted back and forth simultaneously, and, to this end, are connected to a universal bar 147, which extends across the machine to span the several registers, as shown in Figures 4 and 5, the ends of said bar 147 slightly overlapping the outer side plates 97 of the first and last registers. Movement of the universal bar 147 back and forth is transmitted from the cross-shaft 52, which, as previously explained, has a reciprocatory rotation, resulting from its connection with the general-operator racks 46. To move the universal bar 147 back and forth without skewing, it is engaged at two widely-spaced places along its length by a pair of slides 148, which may be shaped as best seen in Figures 3, 5 and 9. The forward end of each slide 148 has a slot 149 which slidably fits a block 150, located and riveted within a slot 151, cut in a post 152 upstanding from the cross-member 98 of the framework and secured to said cross-member by a screw 154, Figure 3. The sides of the slot 151 retain the forward end of the slide 148 laterally, while the block 150 co-operating with the slot 149 in said slide retains the forward end of said slide vertically. The rear end of the slide 148 has a slot 153 which slidably fits a rectangular block 155, which is provided with a hole for a running fit on the cross-shaft 52.

For enabling the cross-shaft 52 to reciprocate the slides 148, there is fastened to said shaft two cams 156, one cam being adjacent each slide 148. There is secured to each slide 148 a closure-plate 157, having a slot 158. Said closure-plate is secured to its slide 148, by screws 159, on the side opposite to which the cam 156 is disposed. There are on each slide 148 a front cam-roll 160 and a rear cam-roll 161, the former being directly mounted on said slide on a headed stud 162, and the latter roll 161 being mounted on the closure-plate 157 by a headed stud 163.

The front roll 160 has an outer flange 164, which may bear against the side of the cam 156 to co-operate with the closure-plate 157 in re-

taining the slide laterally. For such lateral retention of the slide, the top and bottom edges of the slot 158 of the closure-plate overlap the top and bottom edges of the slot 153 in the slide 148, so that said closure-plate bears on the side of the block 155 which in turn bears on one side of the cam 156 which thus retains said slide laterally, the roll-flange 164 bearing on the other side of said cam.

10 For coupling the slide 148 with the universal bar 147, each slide 148 may have a notch 165, which includes at its forward side a tongue 166, which may overlap and underlie the forward edge of the universal bar, and thereby serve to retain the latter at said forward edge. For easy assembling of the parts, the rearward side 165^a of the notch 165 is spaced from the rearward edge of the universal bar, the latter being secured at said rearward edge, however, by means of a block 167 formed as best seen in Figures 3 and 5, said block including a forwardly-projecting tongue 168 which overlaps and underlies the rearward edge of said universal bar. The block 167 is slotted at 169 to embrace the sides of the slide 148, and close 25 the gap between the rearward side 165^a of the notch 165 and the universal bar 147, said block being secured in place by a screw 170.

Connection is made between each latch-bar 115 and the universal bar 147 by means of a pair of links 171 engaging the latch-bar 115 near its ends, and being disposed, therefore, adjacent the fixed plates 97 which support said latch-bar at its ends, as aforesaid, by means of the slots 144. Each latch-bar 115 may, as best seen in Figure 35, have at each end a notch 172 to form with a notch 173 in the link 171 an interlocking joint connecting said latch-bar 115 and link 171. The rearward end of each link has a slot 174 which slidably fits a stud 175 projecting from the inner side of the adjacent fixed plate 97. Thus, by means of said slots 174, studs 175 and the slots 144, the latch-bar 115 and its pair of links 171 are guided for back-and-forth movement and are wholly supported by the register fixed plates 97. 40 For connection with the universal bar 147, each link 171 has a notch 176, Figure 7, the front and rear sides of which may, as seen in Figure 5, embrace said universal bar. Each latch-bar may also carry an anchor-plate 177, having perforations for attaching the ends of the springs 114 that pull the stop-bars 113 forward as they are unlatched. In order that the pull of said springs 114 may have a downward component, the anchor-plate 177 is somewhat below the spring-ends 45 attached to said stop-bars 113, said downward component of the spring-pull serving to pull the forward end of the stop-bar down when the latch-bar 115 is moved forwardly, and thereby causing the stop-bar to become relatched. For thus positioning the anchor-plate 177, it is spaced from the latch-bar 115 by collars 178, and is secured by screws 179.

Means to ensure positive relatching of the stop-bars 113, and designed to supplement the downward pull of the springs 114, include, for each register and the set of stop-bars 113 therein, a swingable bail 180, having side arms 181, whereby said bail may be pivoted to the inner sides of a pair of fixed plates 97, by pivot-screws 182, threaded into said fixed plates. Said bail 180, extending transversely of the several register-bars 21 and stop-bars 113 of the register, is provided with slots 183, to clear said register-bars and afford prongs, the lower ends of which, reaching 75 downwardly between the register-bars, may en-

gage and push against the top edges of the stop-bars 113. It will be seen that if said bail 180 is pressed downwardly after the latch-bar 115 has been moved forwardly for relatching the stop-bars 113, each stop-bar will be positively urged down, to ensure that the latching edge 116 of each stop-bar 113 will be properly caught by said latching bar 115. For imparting such downward movement to the bail 180, the right arm 181 of each bail is extended rearwardly to include a lug 184, which may be engaged by suitable means to effect the depression of said bail 180. Such means may be formed on a cross-shaft 185, in the form of teeth 186, which, in a revolution of said shaft, pass over and displace said lug 184, with a consequent depression of the bail 180. Said teeth may be separately inserted in the cross-shaft 185, there being one tooth for each register, each tooth having a step 188, which is received by a transverse hole in the shaft 185, and is secured by a nut 189, which may be countersunk below the surface of said shaft. The shaft 185 receives a complete revolution during a computing-machine cycle to fulfill operation of means (not shown) for controlling other operations of the computing mechanism, said complete revolution being derived from the reciprocatory motions of the cross-shaft 52 and left-hand rack 46.

To this end, the cross-shaft 52 is provided with an additional sector 190, which may engage a sector 191 loose on the shaft 185. Another sector 192, also loose on said shaft, is coupled to the left rack 46 by an intermediate gear 193, Figure 4. A clutch-device 194, disposed between the sectors 191 and 192, is keyed to the shaft 185 and is arranged to receive from the opposite rotations of said sectors 191 and 192 one continuous rotation as the cross-shaft 52 and rack 46 are reciprocated once in a computing-machine cycle. Details of the construction of said clutch-device 194 and its operation with respect to the sectors 191 and 192 are fully set forth in my original application, Serial No. 324,353 (now Patent No. 1,927,951, dated September 26, 1933). The sector 191 is retained by a collar 202, fastened to the cross-shaft 185, the latter being journaled in the side members 47 of the framework. Inasmuch as the bail 180 is depressed when the latch-bar 115 is in its forward position, restoration of said bail may be effected by the rearward movement of said latch-bar 115. To this end, the left arm 181 of said bail has a downward and rearward extension 203, whose lower end, see Figure 10, is in the path of the latch-bar 115 when said latch-bar is to be moved rearwardly. Rearward movement of said latch-bar 115 will therefore cause upward displacement of the bail 180 as seen in Figure 11. While the latch-bar 115 is in said rearward position, the bail 180 is held up and so cannot interfere with upward movement of the stop-bars 113, such upward movement taking place whenever a carrying lever 126 is operated.

The cross-shafts 52 and 185 and the general-operator cross-bar 45 may be supported at their middle portions by a transverse bar 196, secured to and fastened to the front and rear cross-members 98, 99 of the framework. The general-operator cross-bar 45 may bear directly upon the top of said transverse bar 196. To enable said bar 196 to support the cross-shafts 52 and 185, each 70 of the latter is provided with a grooved collar 197, which may have a running fit on its shaft, and one flange of which may bear upon the upper edge of an angle-piece 198, secured to and extending upwardly from the transverse bar 196. The 75

grooves of said collars 197 receive slots 199^a formed in a plate 199, which is attached to the upstanding side of the angle-piece 198 by screws 200. The plate 199 and grooved collar 197 constitute middle bearings for the shafts 52, 185, which may be easily dismantled or reassembled to facilitate removal or installation of either shaft 52 or 185. It will further be noted that the arrangement of the slides 148 and of the mounting and operating means therefor is also conducive to easy assembly and disassembling of the parts. Furthermore, any register may be easily removed when the screws 201, which secure it to the cross-member 98, Figure 10, are removed. The bar 147 may be retained against endwise displacement by two pins 147^a projecting upwardly therefrom and abutting the sides of the transverse bar 196.

The contours of the cams 156 may be so arranged that the latch-bars 115 and the bars 113, the latter having the register-bar stops 112, are shifted forwardly gradually, but soon enough to bring the stops 112 into effective position before a register-bar reaches the end of its advance movement, and similarly the return of the latch-bar 115 is also effected gradually through said arrangement of the contours of the cams 156, the return of the latch-bar 115, and consequently of the bars 113, not commencing, however, any sooner than say, the time at which the returning cross-bar 45 picks up the farthestmost advanced register-bar.

Alignment and location of the teeth of the computing-wheel pinions 89 may be secured by individual spring-pressed detents 204, which fit the tooth-spaces of said computing-wheel pinions 89. Said detents 204 may be swingably mounted and spaced on the shaft or cross-member 95 and their springs 204^a may be light enough 40 in comparison with the springs 114 so as not to unduly impede the "carrying" force of said latter springs.

As an illustration of the operation of the computing mechanism, consider the following computing example, in addition:

$$\begin{array}{r} 22 \\ +8 \\ \hline 30 \end{array}$$

50 The operator first sees that the computing mechanism is conditioned for addition. The tappet 31 and a tabulating stop 205 having been properly set in relation to the work-sheet zone in which the first item "22" is to be typed, the operator presses the appropriate denominational tabulating key (not shown), and thereby, through connections not shown, raises the corresponding denominational stop 206 to set the typewriter-carriage 14 at the "tens" column of said zone. 55 The item "22" is then typed on the work-sheet by operation of the numeral-keys 10, and during this operation the "2" index-pins 22 are caused to be set in the "tens" and "units" register-bars 21 of whatever register the tappet 31 is set for, it being understood that if only one tappet 31 is set only one set of register-bars will be indexed, and that by setting two tappets 31, one for one register and one for another, accumulation may be effected in two registers. The indexing of the "2" 65 pins in the "tens" and "units" registering-bars caused the "0" pins of said bars to be displaced upwardly, by means not shown but described in my aforesaid co-pending Patent No. 1,869,582.

70 The number "22" having thus been typed on the work-sheet and corresponding index-pins having

been set, the computing mechanism is now ready to be operated for the accumulation of said number in the computing wheels. To this end, the clutch-device of the power-drive is caused to be engaged by retraction of the usual clutch-trip pin, which may be operated by a suitable key and connections, said clutch-device, trip-pin, key, and connections being of the type shown in the aforesaid patent to Hart. Said clutch-device is of such character that the computing-mechanism driver 55 makes one complete forth-and-back movement and no more, inasmuch as said clutch-device in the normal operation thereof automatically disengages itself at the end of said movement, and the cross-bar 45 therefore makes only one complete forth-and-back movement. Similarly, if the power-drive shown in Figures 2, 15 and 16 be employed, the roller 73 of said drive makes only one revolution and no more, starting from and ending in the position shown in Figure 16.

In the initial portion of the forward stroke of the cross-bar 45, the computing-wheel pinions 89 are caused, by the rocking of the shaft 103, to drop into direct engagement with the register-bar racks 90. As the cross-bar 45 proceeds further in its advance stroke the "tens" and "units" register-bar-engaging fingers 43 on said cross-bar engage the depressed "2" index-pins of the tens and units register-bars which are thereupon advanced two unit-spaces and the tens and units computing wheels 20 are also rotated clockwise two unit-spaces. Before the rack-engaging fingers 43 engaged the depressed "2" pins, the register-bar stops 112 on bars 113 were caused, by the rearward movement of the latch-bar 115, effected by its operating connections, to be moved rearwardly to the position indicated in Figure 9 or 12, and in which position said stops abut the depressed "2" pins of the fully-advanced register-bars. At the end of the advance of said register-bars, the relative positions of the register-bar stops 112, the register-bar-engaging fingers 43, and the cross-bar 45 in respect to the depressed "2" index-pins, are as indicated in Figure 12, from which it will be seen the advanced register-bars are secured against overthrow and rebound.

The cross-bar 45 having now fully advanced the "tens" and "units" register-bars for accumulation of the number "22", said cross-bar is caused, through the effect of the cam-slot portion 70, Figure 11, or the curved portion 78, Figure 15, to be stationary for an interval of time, this stationary period in the operation of the cross-bar 45 affording time for carrying. No carrying operation, however, takes place during the accumulation of the number "22", it being understood that all the register-wheels were originally set at "0". The cross-bar 45 only commences its return after the roll 65 has reached, in the return movement of racks 46, the bottom of said cam-slot portion 70. Similarly, in the power-drive shown in Figure 15, after passing the curved portion 78 of the cross-bar links 75 the continued revolution of the driving roller 73 causes the cross-bar 45 to be returned.

In the initial portion of the return stroke of the cross-bar 45, the computing wheels are caused, by reverse rocking of the shaft 103, to be disengaged from the register-bar racks 90 so as not to be reversed when the cross-bar 45 picks up the register-bars. The cross-bar 45 in its return movement picks up the advanced register-bars by engaging the projections 195 thereof, and,

with the co-operation of the spring-device 42, returns them fully to their normal positions, as seen in Figure 1. The cross-bar 45 itself does not move back far enough to effect the full return of the register-bars. Said spring-device 42 completes the return of said register-bars in order to leave a gap 187 (Figure 10) which affords sufficient room for the serial advance of the register-bars for indexing of the pins 22. During the return stroke of the cross-bar 45 and its operating train, including the cross-shaft 52, the register-bar-stops 112 on bars 113 are moved forwardly again by the advance of the latch-bar 115 effected through its described operating connections with said shaft 52 to leave room between the "0" pins and said stops for the aforesaid serial advance of the register-bars for pin-setting.

Near the end of the cross-bar 45 return movement, pin-restoring balls not shown, but described in my original application No. 324,353, are operated to effect restoration of the "2" pins of the "tens" and "units" register-bars by resetting the "0" pins of said register-bars.

After an accumulating cycle of the mechanism for the item "22" is thus completed, the type-writer-carriage 14 being returned either before or after said cycle and the platen line-spaced, the next number "8" is typed on the work-sheet after tabulating said carriage 14 to the units column. The "8" pin will thereby be set in the "units" register-bar with a corresponding restoration of the "0" pin of said register-bar, and the clutch-device of the power-drive is tripped to again operate the mechanism to accumulate "8". During this accumulating operation, the "units" register-bar advances eight spaces, thereby revolving the "units" computing wheel also eight spaces clockwise, and causing it to pass the carrying point, inasmuch as it previously registered "2" and now registers "0". As the "units" wheel so passes the carrying point, its carrying tooth 125 rocks the "units" carrying lever 126 and releases the corresponding stop-bar 113 to effect a forward advance of the register-bar-engaging finger 43 for the "tens" register-bar which is thus advanced one unit-space. The "tens" wheel therefore, instead of showing "2", now shows "3". In this particular example, the carrying tooth 125 of the units wheel released the stop-bar 113 as the units register-bar was moving through its last unit-space of movement, so that the carrying advance of the "tens" register-bar is probably effected by the power of the spring 114 of the released stop-bar 113, the actual carrying advance of the "tens" register-bar probably taking place while the cross-bar 45 is in its stationary period.

During the return stroke of the cross-bar 45 and the accompanying counterclockwise rotation of the cross-shaft 52, all the stop-bars 113, except the one which was released for carrying and whose lever 118 therefore already abuts the rod 123, are moved forwardly again by the forward movement of the latch-bar 115, connected to said cross-shaft 52, said latch-bar passing slightly beyond the latching edge 116 of the released stop-bar, and thereby causing the released stop-bar to be latched again, as indicated in Figure 1. Similarly the latch-bar 115 also passes, it may be noted, slightly beyond the latching edges 116 of the other bars 113, after the levers 118 of said other bars in their forward movement finally abut said rod 123. In the relatching of the bars 113 the balls 180 co-operate with the springs 114 in forcing the bars downward,

so that the latching edges 116 are sure to be caught by the latch-bar 115 when the latter moves rearwardly in a succeeding cycle. As best seen in Figure 10, the balls 180 are down when the machine is at rest in its normal position, the several ball-actuating teeth 186 being then over the lugs 184 of their respective balls. This locks the carrying bars 113 against accidental unlatching while the machine is at rest. Aside from the release and restoration of a stop-bar 113 and its related parts for carrying, the operations of the mechanism are the same for the accumulation of "8" as were the operations for the accumulation of "22".

In the subtractive computing example

$$\begin{array}{r} 10 \\ -1 \\ \hline 9 \end{array}$$

"10" is first typed and indexed in the "tens" and "units" register-bars, and the computing mechanism is operated to accumulate "10" as aforesaid. The "1" pin in the "tens" register-bar, which, it may be noted, happens to be the only pin indexed, is restored at the end of the accumulating operation by resetting of the "0" index-pin. The "1" to be subtracted is now typed (the carriage having been returned and the platen line-spaced), and correspondingly the "1" index-pin of the units register-bar is set, it being noted that the pin which is set always has the same value as the operated numeral-key, irrespective of whether the item is to be added or subtracted. It may also be noted that in subtraction the zero-pin of a register-bar is also, as in addition, restored by the setting of a higher pin in said bar.

In the accumulating operation of the computing mechanism which is now to take place, the computing wheels must be rotated reversely or counterclockwise in order that the "1" may be subtracted. Before a computing cycle is initiated therefore by engagement of the clutch-device of the power-drive, a subtraction-key (not shown) must be first pressed in. By pressing in the subtraction-key, mechanism not shown, but of the type shown in my original application No. 324,353, is conditioned so as to be effective during the computing-machine cycle to shift the computing-wheel frame 93 rearwardly before the register-bars advance, and then forwardly again before the register-bars return, such rearward and forward shifting of said frame 93 causing the computing wheels 20 to engage the intermediate pinions 91 before the register-bars advance and to be disengaged before said register-bars are returned. The rock-shaft 183 remains stationary during the subtractive accumulating operation.

With the computing wheels 20 moved rearwardly into engagement with the intermediate pinions 91, the forward movement of any pinion 21 causes its computing wheel to be rotated counterclockwise. The "units" wheel which registers "0" is therefore rotated one space counterclockwise from said "0" position to the "9" position, and thus the carrying tooth 125 of said "units" wheel displaces its carrying lever 126, causing the corresponding bar 113, which extends to the "tens" register-bar to be released, with the result that said "tens" register-bar advances one unit-step forwardly. Thereby the "tens" wheel, driven through its intermediate pinion 91, is rotated counterclockwise one step or from "1" which it previously registered to "0", and the computing wheels as a whole now indicate "9", which is the correct result of the above subtractive computing example.

5 Except for the reversed rotation of the computing wheels caused by their engagement and disengagement with the intermediate pinions 91 instead of with the register-bar racks 90, the accumulating operation of the mechanism and the preparatory indexing of the pins 22 are the same for subtracting a number as for adding a number, that is to say, the operation of the carrying trains as the same in both cases, and the restoration 10 of the index-pins, by resetting all "0" pins, is also the same in both cases.

15 At the end of a subtractive computation the mechanism may be restored to its normal additive condition by releasing the subtraction-key, whereupon the mechanism, mentioned as aforesaid as being disclosed in my original application No. 324,353, is conditioned to rock the shaft 103 during an additive computing-machine cycle.

20 Variations may be resorted to within the scope of the invention, and portions of the improvements may be used without others.

Having thus described my invention, I claim:

1. In a computing machine; a reciprocatory register bar having a normally set zero pin and 25 a normally unset higher pin, said zero pin being restorable concomitantly with the setting of the higher pin, said register bar being slightly advanceable from a normal position preparatory to effecting pin setting, a reciprocatory general 30 operator for engaging the set higher pin and advancing said register bar, during a cycle of said general operator, after the pin-setting operation, said register bar being restored to normal position at the end of the cycle, a stop for confronting the set pin to counteract undue advance 35 of the register bar by the general operator

in said cycle, said stop being normally retracted from an effective position to permit the slight advance of the register bar for pin setting, said stop in its effective position confronting the zero pin when said register bar is in normal position, and means cooperative with said general operator to place automatically said stop in effective position during said cycle.

2. In a computing machine; a reciprocatory register bar having a normally set zero pin and a normally unset higher pin, said zero pin being restorable concomitantly with the setting of the higher pin, said register bar being slightly advanceable from a normal position preparatory to effecting pin setting, a reciprocatory general 15 operator for engaging the set higher pin and advancing said register bar, during a cycle of said general operator, after the pin-setting operation, said register bar being restored to normal position at the end of the cycle, a stop for confronting the set pin to counteract undue advance of the register bar by the general operator in said 20 cycle, said stop being normally retracted from an effective position to permit the slight advance of the register bar for pin setting, said stop in its effective position confronting the zero pin when said register bar is in normal position, and means cooperative with said general operator to place automatically said stop in effective position during said cycle, said means including a 25 timing device operative to place said stop in effective position before the register bar reaches the end of its advance by the general operator and to restore said stop to retracted position before the end of the cycle.

35 HENRY L. PITMAN.
